UNITED STATES PATENT OFFICE.

JOSEPH J. JOHNSON, OF LEBANON, OHIO.

HARNESS.

SPECIFICATION forming part of Letters Patent No. 236,819, dated January 18, 1881.

Application filed September 13, 1880. (No model.)

To all whom it may concern:

Be it known that I, JOSEPH J. JOHNSON, of Lebanon, in the county of Warren and State of Ohio, have invented a new and useful Improvement in Harness, of which the following is a specification.

My invention consists in a novel construction and arrangement of devices used in connection with the back-strap and the collar, whereby provision is made for dispensing with traces or tugs for pulling and with breechings for holding back, as hereinafter described.

In the accompanying drawings, Figure 1 is a side view, representing a portion of the right-hand side of a harness embodying my improvements. Fig. 2 is a transverse vertical section taken in the line *xx* of Fig. 1. Fig. 3 is a horizontal section taken in the line *yy* of Fig. 1. Figs. 4 and 5 are detail views.

Similar letters of reference indicate corresponding parts.

A represents a portion of the back-strap.

B is a metallic plate riveted to the rear side of the back-strap and concealed by the covering of said strap.

C is a metallic bar lying against the plate *B*, but not secured thereto.

D is a metallic keeper lying against the outside of the strap *A*, and secured thereto by screws *d* passing through it and through said strap *A*, plate *B*, and bar *C*.

E is a metallic bar, held in place in a horizontal position by the keeper *D*, and having near its ends two lugs, *e e*, which allow it to slide rectilinearly in said keeper for a certain distance back and forth, but prevent it from coming entirely out of place. The lugs *e e* are perforated so as to form loops or eyes. A plate, *f*, lies between the bar *E* and the strap, so as to prevent friction against said strap.

G is a cylindrical sleeve, made in two parts, hinged together at *g*, and provided with a screw, *h*, for securing the two hinged parts to each other, so as to clamp between them the vehicle shaft or thill *i*. The sleeve *G* is provided with two hooks, *J J*, for engagement with the loops or eyes of the lugs *e e*, so as to

connect it to the bar *E*, as shown in Figs. 1 and 2, in which position the sleeve is held by means of sliding spring-bolts *K K*, the points 50 of which bear against the loops or eyes when the hooks *J* are engaged therewith. Said bolts are provided with thumb knobs or studs for retracting them, when necessary, in order to disconnect the sleeve from the bar *E*. If 55 desired, they may also be provided with straps *l* for the same purpose.

In the bar *E* is a groove, in which rests a strap, *m*, leading from the collar. The strap *m* is held in place in the groove by means of 60 screws or bolts *s*.

When the harness is in use the bar *E*, having the sleeve *G* attached thereto, slides back and forth in the keeper *D* in accordance with the motions of the horse.

By attaching the shafts or thills to the sleeves and then connecting said sleeves to the back-strap and the collar, as above described, I dispense with the necessity for employing either traces or tugs for pulling or 70 breechings for holding back.

The harness may be adjusted to horses of different sizes by removing the screws or bolts *d* and *s*, and raising or lowering the keeper *D*, and lengthening or shortening the strap *m*, 75 and then replacing said screws or bolts.

Having thus fully described my invention, I claim as new and desire to secure by Letters Patent—

1. The combination, with the back-strap *A*, 80 of the plate *B*, bar *C*, and keeper *D*, as shown and described, for the purpose specified.

2. The combination, with the keeper *D*, of the bar *E*, provided with the lugs *e e*, as shown and described, for the purpose specified. 85

3. The combination, with the bar *E*, provided with the perforated lugs *e e*, of the sleeve *G*, provided with the hooks *J J* and spring-bolts *K K*, as shown and described, for the purpose specified.

JOSEPH J. JOHNSON.
